UNITED STATES PATENT OFFICE.

HARRY W. BURLEIGH, OF FRANKLIN, NEW HAMPSHIRE.

WRENCH.

SPECIFICATION forming part of Letters Patent No. 415,379, dated November 19, 1889.

Application filed February 5, 1889. Serial No. 298,696. (Model.)

To all whom it may concern:

Be it known that I, HARRY W. BURLEIGH, a citizen of the United States, residing at Franklin, in the county of Merrimac and State of 5 New Hampshire, have invented certain new and useful Improvements in Wrenches, of which the following is a specification.

The object of this invention is to provide means for the automatic adjustment of a 10 wrench to a nut or other object to be turned by it, also to enable the wrench to remain in position after having been once applied to a nut until removed by an operator.

The invention will be readily understood 15 by reference to the following specification and claim, and the accompanying drawings, forming an inseparable part thereof, of which—

Figure 1 represents an elevation of a wrench 20 embodying my improvements, Fig. 2 being a sectional elevation of the same; and Fig. 3 is an elevation showing the reverse side to that shown in Fig. 1.

The arm A has at one end an integral gripping-jaw a, and at the other end may be attached a handle B. An adjustable gripping-jaw c is formed upon an arm C, which is provided with tongues c' c², entering, respectively, the slots a' a², formed in the arm A for 30 the purpose of attaching the parts A and C together. To the tongue c' is attached a plate D, which may be perforated with holes for receiving screws d, which are threaded to openings in the said tongue c', as indicated in Fig. 2.

The metal between the slots a' a² of the arm A is grooved upon the side adjacent to the arm C, in order to make room between said parts for a spring E, which is expanded 40 between the shoulder a³ of the arm A and one end of the tongue c' of the arm C, the said spring spending its force upon the said tongue. The adjustable jaw c is thereby caused to automatically close itself upon the 45 stationary jaw a.

In order to hold the jaws the required distance apart to receive a nut of given size and to enable them to operate the nut without spreading farther apart, one side of the lower 50 part of the slot a² may be serrated, as shown

at a⁴, and a pawl F may be pivoted at G to that end of the arm C opposite to the jaw c for engaging the teeth or serrations a⁴, to which may be applied a suitable spring H for holding it to its work, said spring being attached in any 55 convenient manner to the arm C, with its free end resting against said pawl to accomplish the desired result. To open or separate the jaws, the said pawl must be disengaged from the teeth or serrations a⁴. This may be conveniently accomplished by forming an arm f upon or attaching such arm to the pawl F, said arm being preferably provided with a finger-piece f', projecting in a direction parallel, or nearly so, with the handle B. By 60 this construction an operator, when about to use the wrench, may place a finger or thumb of that hand with which he grasps the handle B upon the finger-piece f' of the pawl and press it gently toward said handle B, 70 which motion first releases said pawl from the teeth a⁴, and when this is accomplished the arm C is drawn toward said handle, which opens or increases the space between the jaws a c. This done, the wrench may be applied to a nut or other article to be turned, and by removing the finger or thumb from the piece f' the action of the spring E automatically adjusts the jaws thereon, and the pawl F, in connection with the teeth a⁴, sets 75 80 and holds them to their work.

Having described my improvements, what I claim as new, and desire to secure by Letters Patent, is—

A wrench comprising a stationary member 85 having at one end a gripping-jaw and slots, as shown, and serrations or ratchet-teeth formed upon one side of one of said slots, a movable member having at one end a gripping-jaw and at the other end a pawl for engaging said ratchet-teeth, and a suitable spring adapted to compress said jaws, all combined substantially for the purpose set forth.

In testimony whereof I affix my signature in 95 presence of two witnesses.

HARRY W. BURLEIGH.
